DESIGN FOR A SLIPPER OR LIKE ARTICLE

Marvin Fox, Hanover, Pa., assignor to H. Jacobs
& Son, Inc., a corporation of New York

Application March 16, 1942, Serial No. 106,210

Term of patent 7 years

To all whom it may concern:

Be it known that Marvin Fox, a citizen of the United States and resident of Hanover, in the county of York and State of Pennsylvania, has invented a new, original, and ornamental Design for a Slipper or like Article, of which the following is a specification, reference being had to the accompanying drawing, forming part thereof, in which Figs. 1 and 2 are side elevational and plan views, respectively, of a slipper showing my new design, and Fig. 3 is a rear end view thereof.

My design for a slipper of the specific configuration as shown is characterized by a high vamp and high upper quarter with the lower portion of the vamp extending rearwardly and overlapping the lower portion of the upper quarter extending forwardly so as to form acute angle openings on both sides of the slipper, in combination with a one-piece sole and heel, all as illustrated by the drawing.

I claim:

The ornamental design for a slipper or like article, as shown and described.

MARVIN FOX.
